NAPKIN HOLDING DEVICE

Luther B. Barth, Glen Rte., Aitkin, Minn.
Filed Aug. 11, 1959, Ser. No. 833,069
2 Claims. (Cl. 45—68.4)

This invention relates to a holding means to be used in connection with a place mat for a dining table or directly in connection with such a table.

It is desirable to have some means for holding a napkin particularly after the napkin has been used. Generally a napkin after having been used is crumpled up and placed on the table making an unpleasing sight. It is desirable to have a convenient means for holding said napkin below a table top level.

It is an object of this invention, therefore, in connection with a table, to provide means for holding a napkin below the surface level of a dining table.

It is another object of this invention in connection with a place mat to provide a bracket removably secured to said place mat and depending over the edge portion of a table and being adapted to have a napkin removably secured therein.

It is a further object of this invention to provide, in connection with a place mat for a table, a right-angled bracket having portions in the plane of and being adapted to be removably secured to said place mat and having a depending reversely curved U-shaped portion adapted to have a napkin supported therein.

It is still another object of this invention to provide a bracket having a ring portion of flat, thin, substantially rigid material adapted to be disposed beneath a place mat on a table or beneath a dish such as a dinner plate and having a depending reversely curved U-shaped portion adapted to support a table napkin below the surface level of said table.

It is also an object of this invention to provide a substantially U-shaped, reversely curved bracket having integral therewith portions adapted to be removably secured to the edge portion of a table.

These and other objects and advantages of the invention will be fully set forth in the following description made in connection with the accompanying drawings in which like reference characters refer to similar parts throughout the several views and in which:

FIG. 1 is a perspective view showing a fragmentary portion of a table top and applicant's device in operating position;

FIG. 2 is a top plan view of a broken portion of a place mat with applicant's device shown in an alternate position on dotted line;

FIG. 3 is a view in vertical section taken on line 3—3 of FIG. 2 as indicated by the arrows;

FIG. 4 is a top plan view of applicant's device in modified form;

FIG. 5 is a view in vertical section taken on line 5—5 of FIG. 4 as indicated by the arrows;

FIG. 6 is a perspective view showing a fragmentary portion of a table top and applicant's device in operation position with some parts thereof in dotted line; and

FIG. 7 is a perspective view of a modified form of applicant's device.

Referring to FIGS. 1-3 a fragmentary portion of a table 10 is indicated of common construction and having a top portion substantially parallelepiped in form. Disposed on said table in position is a place mat 12 having a dinner plate 13 indicated thereon. Said place mat which may be variously formed is here indicated as being circular in form having a decorative open-work doily 14 thereon. Said place mat preferably is made of a somewhat rigid

2

sheet material having some thickness as will be herein-after indicated.

Said place mat 12 has formed therein a pair of parallel passage ways 15 and 16 of small transverse dimension extending directly inwardly from an edge portion thereof for some distance as indicated in FIGS. 2 and 3.

Adapted to be used in connection with said place mat 12 is a bracket 18. Said bracket which may be variously formed is in the embodiment of the invention here disclosed indicated as being formed of rod-like material of small transverse dimension being somewhat resilient or spring-like. Said bracket is formed by first being reversely curved and having its closed end portion bent at a right angle to the free end portions thereof and then reversely curved to form a depending U-shaped portion 20. The free end portions 21 and 22 of said bracket are adapted to extend away from said portion 20 and be inclined outwardly in a direction somewhat away from one another to have said free end portions spaced somewhat further apart than the distance between said passage ways 15 and 16. Said free end portions 20 and 21 are urged together to be disposed within said passage ways 15 and 16 to frictionally engage the remote sides of said passage ways to be removably held therein. With reference to FIG. 1, a member 24 indicated as being a folded napkin is shown held in operating position in said bracket 18.

The use of applicant's device is quite obvious from its description. Place mat 12 may be provided prepared with passage ways 15 and 16 therein and said brackets 18 may be removably positioned therein as indicated and easily removed therefrom for storage purposes.

With reference to FIG. 4, a modification of applicant's device is shown comprising a substantially annular member 30 preferably formed of stiffened material somewhat resilient or spring-like and of small transverse dimension. Integral with said portion 30 and extending in a direction outwardly therefrom in the same plane thereof are portions thereof forming a pair of parallel portions 32 and 33 joined at their remote ends to form a closed end portion 35 which is here shown bent downwardly at substantially a right-angle to the plane of said annular portion and reversely curved to form depending U-shaped bracket. The ring portion 30 is preferably formed to be in a substantially flat condition so that a place mat or a plate may be directly placed thereon to provide sufficient weight to hold the same in position. With reference to FIG. 5, a plate 38 is indicated as having been placed over said portion 30 and said depending bracket portion 35 will very conveniently support a napkin or the like therein below the surface level of a table. Said annular member 30 is here indicated as having extending thereacross a member 31 of thin flexible sheet material whereby said member 30 may be retained in position by a plate or dish of smaller dimension being placed centrally thereon.

With reference to FIG. 6, applicant's bracket 18 is shown used directly in connection with a table 40 instead of in connection with a place mat as above described. A broken edge portion of table 40 as indicated having formed therein, a pair of substantially parallel spaced passage ways 41 and 42 spaced apart somewhat less than the distance between the free end portions 21 and 22 of said bracket 18 whereby said free end portions are urged in a direction toward one another to be disposed in said passage ways 41 and 42 to frictionally engage the remote sides of said passages.

With reference to FIG. 7, a modified form of applicant's device is shown comprising a substantially U-shaped plate member 45 formed of spring-like material having sides 46 and 47 spaced apart by the end portion 48 the distance of the thickness of a table top. Said sides 46 and 47 will be inclined somewhat toward one another

in the direction of their free ends. A somewhat U-shaped portion 50 is shown struck out of said side 47 and reversely curved upwardly in the direction of the side 46 to form a substantially U-shaped bracket. Thus, applicant's device 45 is adapted to be placed over the edge portion of a table to frictionally engage the same having said bracket portion 50 extending outwardly of said table below the surface thereof for supporting therein an object such as a napkin.

Thus, it is seen that I have provided a very simply constructed bracket having a high degree of utility for use in connection with a place mat on a table or for use directly in connection with a table for supporting objects such as napkins conveniently below the surface level of a table.

It will of course be understood that various changes may be made in the form, details, arrangement and proportions of the parts, without departing from the scope of applicant's invention, which, generally stated, consists in a device capable of carrying out the objects above set forth, in the parts and combinations of parts disclosed and defined in the appended claims.

What is claimed is:

1. A structure of the type indicated having in combination, a place mat of small thickness, an elongated U-shaped member having a free end and a closed end, its

free end portion removably disposed in said mat in the plane thereof through an edge portion thereof, said member adjacent the edge portion of said mat being bent out of the plane of said mat to form a substantial angle therewith and the closed end portion of said member being reversely bent in a direction oppositely of said free end portion to form a napkin holding bracket.

2. A structure of the type indicated having in combination, a place mat such as is disposed under a plate as on a table, an elongated U-shaped member having a free end and a closed end, its free end portion being integral with said mat, said member being bent adjacent said free end portion to form at least a right angle, with the plane of said mat and the closed end portion of said member being reversely bent in a direction oppositely of said free end portion to form a napkin holding bracket.
